UNITED STATES PATENT OFFICE.

FRANK KORTICK, OF SAN FRANCISCO, CALIFORNIA.

SNAP-HOOK.

SPECIFICATION forming part of Letters Patent No. 225,756, dated March 23, 1880.

Application filed October 13, 1879.

To all whom it may concern:

Be it known that I, FRANK KORTICK, of the city and county of San Francisco, and State of California, have invented an Improvement 5 in Snap-Hooks; and I hereby declare the following to be a full, clear, and exact description thereof.

My invention relates to certain improvements in snap-hooks such as may be employed 10 to connect various parts of a harness, and for any other purpose where it is necessary to have an easy means for connecting and disconnecting parts; and it consists in the formation of a hook having a spring latch-piece, 15 which allows the link or other attachment to be easily connected with the hook or detached therefrom, as will be more fully described by reference to the accompanying drawings, in which—

20 Figure 1 is a view of my hook. Fig. 2 is a section of Fig. 1.

A is a hook, having the extended shank B, with the eye or other means of connection at its opposite end. This shank is made full up 25 on its inner side, so as to allow a hole to be made to receive a pin, C, by which the latch or locking portion D is secured to the shank. This latch is bifurcated and made with a cross-bar, a, connecting the two legs, and it 30 extends forward so that its upwardly-curved points d stand just opposite to the point of the

hook, and when they are in that position it will be impossible to remove any link or loop from the hook.

Beneath the latch, and just in front of the 35 pin C, is the spring E, lying beneath cross-bar a, which holds the points d of the latch up. This spring may be spiral, flat, or any suitable form, and the points of the latch are so formed that a loop or ring may be introduced 40 to the hook by simply pushing it against these points. The spring will allow the points to retreat or be forced backward until the ring has entered, when it will immediately force them out to their original position. The rear 45 end of the latch projects beyond the pin, so as to form a stop, i, which prevents the points d from being forced outward too far.

Having thus described my invention, what I claim as new, and desire to secure by Letters 50 Patent, is—

The hook-piece A B, provided with an eye, in combination with a bifurcated latch, D, having two points, d d, a cross-bar, a, and a stop, i, and the spring E, all constructed and ar 55 ranged as set forth.

In witness whereof I have hereunto set my hand.

FRANK KORTICK.
